UNITED STATES PATENT OFFICE.

JOHN B. MONTAGUE, OF FRANKLIN, KENTUCKY.

SASH FASTENER AND HOLDER.

SPECIFICATION forming part of Letters Patent No. 251,915, dated January 3, 1882.

Application filed November 18, 1881. (No model.)

To all whom it may concern:

Be it known that I, JOHN B. MONTAGUE, of Franklin, in the county of Simpson and State of Kentucky, have invented certain Improvements in Sash Holders and Locks, of which the following is a specification.

This invention relates to a combined sash holder and lock; and it consists in a slotted eccentric provided with a sliding locking-bolt, 10 and prismatic rod or stem extending through said parts and projecting out through the window-casing.

It further consists in certain other details of construction, hereinafter more fully explained.

In the accompanying drawings, Figure 1 represents a perspective view of the improved device, with the window frame or casing broken away to show the position of the parts; Fig. 2, a view showing the parts separated one from another; Fig. 3, a vertical section through the device, showing the locking-bolt shot forward.

The object of my invention is to produce a cheap and simple device adapted to hold or securely lock a sash in any desired position, 25 and which may be applied readily to sash, regardless of their thickness or of the depth of the window-frame.

The construction will be readily understood by referring to the drawings, in which A represents the case or sheath within which the eccentric or dog B and the locking-bolt C are arranged, the locking bolt sliding longitudinally in the eccentric or dog, as shown. The case or sheath A is formed with a semicircular seat 30 or depression, a, in which the end of the dog B, correspondingly rounded, is seated, thus affording for the dog a firm seat or support in which it may freely turn or rock. The sheath is further provided with side arms, b, having 35 horizontal slots c extending lengthwise of the same, the slot of each arm being enlarged and made of circular form at the rear end, as shown at c'. The dog or eccentric is formed with a slot, d, of corresponding length and width, but 40 without the circular enlargement at the rear end, and the inner or rear end of the sliding bolt C is provided with a square opening, e, in line with the slots c d, as shown. A square spindle or shank, D, passes through the window frame or casing and through the slots c d and opening e, and this shank remains nor-

mally in the circular enlargement c', where it may freely turn to operate the dog or eccentric, which, having its sharp upper edge somewhat above its center of motion, falls against 55 the side of the sash, the weight of which tends to urge the dog to a horizontal position, thereby the more firmly forcing it against the sash and holding the latter at any point to which it may be raised. It will be seen that as the sash 60 is raised the dog will swing up and release it, but that said dog will automatically lock the instant the sash begins to descend.

In order to release the dog when it is desired to lower the sash it is simply necessary 65 to turn the spindle or shank, which is provided with a knob or handle for that purpose, whereby the sharp edge will be thrown upward and inward away from the sash.

In order that the sash may be locked firmly 70 against movement either up or down, the sliding bolt is arranged to enter recesses or sockets f formed in the sash at suitable points; and it is for the purpose of permitting the shank D to be moved in the direction of the 75 length of the bolt that the case or sheath and the dog are slotted.

By simply moving the shank sidewise it will be seen the bolt C will be projected past the end of the dog B and into the opening or socket 80 f, brought into line therewith, as shown. The reverse movement of the shank of course serves to retract the bolt.

The slots c in the arms b of the case or sheath A are of just sufficient width to receive the shank 85 D when it is turned square with the same, its upper and lower faces bearing directly against the sides of the slots. Hence when the bolt is moved forward the shank, just fitting the slot, cannot turn therein, and therefore the locking-bolt C cannot swing up or down, but will retain the sash firmly in place.

In order that the device may be applied to frames of varying depths, the shank D is made of the greatest length that is likely to be required in any case, and is passed freely through the parts A B C, either being allowed to extend beyond the same into a recess in the frame or cut off at the proper point, as found convenient.

In order to retain the shank in place it is formed with a shoulder and provided with a

rosette or plate, F, slotted to permit the movement of the bolt sidewise, as above explained, as is also the frame through which the shank passes.

5 I am aware that it is not new to combine with an eccentric or gravitating locking-dog a sliding locking-bolt, and hence I do not claim this idea broadly considered. I am not, however, aware that any one has hitherto constructed and arranged the parts in the manner herein described.

Having thus described my invention, what I claim is—

15 1. A sash holder and lock consisting of a slotted case or sheath, a slotted gravitating dog or eccentric seated therein, a locking-bolt sliding through the dog or eccentric, and a prismatic shank extending through said parts, substantially as described.

20 2. In a sash-holder, a case or sheath, A, pro-

vided with a curved seat, a, to receive the end of the dog or eccentric, as explained.

3. In combination with the case or sheath provided with arms b, having the circular-ended slots c' c', a slotted dog or eccentric, a 25 perforated locking-bolt sliding within the dog or eccentric, and an operating-shank passed through the slots and perforation and completely filling the latter, but free to turn in the enlarged end of the slots, as set forth. 30

4. The herein-described sash holder and lock, consisting of the case or sheath A, constructed as explained, slotted dog B, bolt C, shank D, and slotted plate F, all combined and operating as set forth.

JOHN B. MONTAGUE.
